UNITED STATES PATENT OFFICE

EDWIN JUELSON, OF CHICAGO, ILLINOIS

PUMP

Application filed November 24, 1928. Serial No. 321,617.

This invention relates to pneumatic pumps and has for its object the provision of a new and improved shape, construction and relation of impeller or fan, and casing, 5 as to produce a maximum air pressure at a given speed.

In the drawings accompanying and forming a part of this application I have shown my improvements as applied to different 10 types of pneumatic cleaners. Fig. 1 is a vertical central sectional view through part of a can type of vacuum cleaner embodying my improvements; Fig. 2 is a horizontal axial view through a part of a portable type 15 suction sweeper embodying my improvements; Fig. 3 is a sectional view according to the line 3—3 of Figs. 1 and 2; and Fig. 4 illustrates a modified form of the device shown in Fig. 1.

20 In all forms of the invention the fan chamber comprises parallel spaced flat walls 1 and 2 and a curvilinear side wall 3 connecting them. The wall 1 is formed with a circular recess 4 in which is rotatably mounted the 25 circular disk 5 constituting the back of the fan or impeller which is directly connected to the shaft 6 of an electric motor, the face of the disk being provided with blades 7, preferably three in number in the case of 30 small high speed devices, although I do not limit myself to this number. Each blade is preferably normal to the surface of the disk, and convexed towards the direction of rotation; and I have also found it advantageous 35 to have the blade so mounted that the arc of such convexity shall pass through the shaft 6 as shown by the dotted line $p-p$ in Fig. 3.

40 I have found it of distinct importance that the side wall be made oblong or oval in shape, its minor dimension being slightly greater than the diameter of the impeller, and its major direction being sufficiently greater than the minor dimension to produce two 45 chambers at opposite sides of the impeller, the outlet 8 communicating with one of these chambers and the inlet 9 being formed in the wall 2 opposite the impeller. For convenience of description I have in Fig. 3 illustrated the major axis A—B and the minor

axis C—D intersecting at the fan shaft 6, and thereby dividing the side wall into four arcuate sections; although it is not necessary that the same be divided exactly here or that the shaft be located on the axes except to the extent hereafter described. Excellent results are obtained when this chamber is an ellipse but I find my best results by making the sections A—C and A—D of parabolic shape. The section CB,—BD is here shown 60 as elliptical. I have further found it advantageous to make one semi-parabola, as A—C, of smaller size than the other semi-parabola A—D and when this is done, to displace the fan shaft slightly eccentrically, the 65 edge of the fan or impeller being nearer that side which is the smaller, and the direction of rotation being such as to cause each blade to sweep past the face of the larger parabola before passing the outlet 8.

70 It is also desirable that the chamber from which the outlet opens should be smaller in total area than the opposite chamber, and that the latter be left without opening.

Owing to the eccentric mounting of the 75 impeller in the chamber the axes A—B and C—D as drawn do not strictly coincide with the parabolic and elliptic axes, although the same are preferably approximately parallel to the axes shown; or if the axes be drawn 80 to coincide, then the shaft 6 may not be located on either axis. The smaller parabola is indicated by the letters a, m the larger parabola by the letters a, n and the space at 85 s is smaller than the space at t .

90 In the apparatus shown in Fig. 1 my improvements are shown as applied to an upright vacuum cleaner comprising an outer receptacle or can 12, the fan chamber being formed in a hollow cover 13 detachably secured thereto, and the motor having a frame 14 carried by the cover and depending inside the receptacle, being surrounded by a filter cell 15 to allow the escape of air while holding back dust or litter. In the form shown 95 in Fig. 2, the fan chamber is set with its plane vertical and carried by suitable wheels 20, the forward wall of the fan casing having a collecting nozzle 21, the rearward wall carrying 100 the motor housing 22, and the fan outlet

8 being connected to a naked dust bag 23. In the form shown in Fig. 4 I have illustrated a slight modification of the parts shown in Fig. 1, the side wall 3 of the fan 5 casing being cast integral with the top plate 2^a, and the bottom plate 1^a being bolted thereto, the fan outlet 8^a being here formed in the side wall 3 rather than in the wall 1^a.

I have found that the construction herein 10 before described and hereinafter claimed produces a pressure or vacuum very much greater e. g. from 50% to 100% more than other forms of fan casings; but it will be understood that it is not necessary to employ 15 at one time all the refinements herein described and that changes in detail can be made so that I do not limit myself in any wise except as specifically recited in my several claims which I desire may be construed 20 each independently of limitations contained in other claims; and furthermore I do not limit my improvements to use in vacuum cleaners since various features of the same are applicable to other kinds of fans and 25 blowers.

Having thus described my invention what I claim is:

1. A centrifugal pump for aeriform fluids of the type having a fan and a casing, characterized by the casing being of oblong shape 20 and having two chambers one at each side of the fan and in the same plane therewith, and a single outlet opening which communicates with one of said chambers.

2. A centrifugal pump for aeriform fluids of the type having a fan and a casing, characterized by the fan chamber being of oblong oval shape with the fan located between its ends and defining therewith two chambers of 35 unequal size, the smaller having an outlet opening.

3. A centrifugal pump for aeriform fluids of the type having a fan and a casing, characterized by the fan chamber being of oblong 45 oval shape with the fan located between its ends and defining therewith two chambers in the same plane with said fan, the fan being closer to one side of said casing than to the other and one of said chambers having an outlet.

4. A centrifugal pump for aeriform fluids of the type having a fan and a casing, characterized by the walls of the casing conforming in part substantially to a segment of a 55 parabola and the outlet being near the vertex of such parabola.

5. A centrifugal pump for aeriform fluids of the type having a fan and a casing, characterized by the walls of the casing conforming 60 in part to the portions of two parabolas each portion extending from substantially the vertex to a distance at one side of the major axis.

6. A centrifugal pump for aeriform fluids of the type having a fan and a casing, characterized by the walls of the casing conform-

ing in part to the portions at one side of the major axis of two parabolas of unequal size.

7. A centrifugal pump for aeriform fluids of the type having a fan and a casing, characterized by the walls of the casing having two adjacent quadrant segments, each conforming substantially to a semi parabola, and the two remaining quadrants conforming substantially each to a quarter ellipse, the fan being located nearer to the sides of the casing than to the ends so as to define two chambers of which the smaller is that defined by the parabolic segments, and an outlet leading from such smaller chamber.

8. A centrifugal pump for aeriform fluids of the type having a fan and a casing, characterized by the walls of the casing having two adjacent quadrant segments, each conforming substantially to a semi parabola, and the two remaining quadrants conforming substantially each to a quarter ellipse, the fan being located nearer to both sides of said casing than to either end and nearer to one side than to the other, there being an outlet from that end of the casing which has the parabolic side portions.

9. A centrifugal pump for aeriform fluids of the type having a fan and a casing, characterized by the walls of the casing having two adjacent quadrant segments, each conforming substantially to a semi parabola, and the two remaining quadrants conforming substantially each to a quarter ellipse, one parabola being smaller than the other, the fan being located nearer to that side of the casing which represents the smaller parabola, and an outlet leading from that part of the casing interior which is nearest the apices of said parabolas.

In testimony whereof I hereunto affix my signature.

EDWIN JUELSON.
